UNITED STATES PATENT OFFICE.

AARON P. STORRS, OF OWEGO, NEW YORK, ASSIGNOR TO STORRS MICA COMPANY, OF OWEGO, NEW YORK, A CORPORATION OF NEW YORK.

TRANSPARENCY AND PROCESS OF MAKING THE SAME.

Application filed July 6, 1922. Serial No. 573,182.

To all whom it may concern:

Be it known that I, AARON P. STORRS, a citizen of the United States, and a resident of Owego, county of Tioga, and State of New York, have invented a certain new and useful Transparency and Process of Making the Same, of which the following is a specification.

My invention relates to transparencies intended primarily to be exhibited or displayed by transmitted light, such, for example as in lamp shades, wall panels, adapted to be illuminated from the rear, columns adapted to be illuminated from the inside, and the like, and formed of natural products such as mica, onyx, and the like material in which discolorations appear, and has for its objects to produce a light transmitting body from natural materials, and which will be highly ornamented in character and of low cost.

These and further objects will more fully appear in the following specification and accompanying drawings considered together or separately.

I have illustrated one embodiment of the invention in the accompanying drawings in which like parts in the several figures are designated by corresponding characters of reference, and in which

Fig. 1 is a perspective view of a block of material having unsymmetrical discolorations.

Figs. 2 and 3 are perspective views of two thin sheets severed from the block, the sheet shown in Fig. 3 being reversed relatively to that shown in Fig. 2.

Fig. 4 is a perspective view showing the sheets of Figs. 2 and 3 superposed.

Fig. 5 is a similar view showing four superposed sheets, each sheet being reversed relatively to each other sheet.

Fig. 6 is a perspective view of a lamp shade formed of panels of four sheets each.

Fig. 7 is a detail sectional view of a panel formed of two sheets of appreciable thickness, and

Fig. 8 is a sectional view of a modification.

I will first describe the process as carried out by the use of materials of the mica division of the hydrous silicates, and particularly mica of the Muscovite group (isinglass, potash mica). It has a perfect basal cleavage, is usually very tough, and the cleavage

lamellæ are flexible, elastic, and transparent. It usually occurs in scales, plates or scaly masses, and it is readily split into thin sheets which form the commercial mica sheets used in stove doors, lamp chimneys, lantern globes or the like.

Frequently the mica is discolored in streaks, blotches, etc., probably by the presence of other minerals and such discolorations are rarely, if ever, symmetrical. When such discolorations or faults occur the value of the mica is very much less than the clear, colorless and transparent sheets or scales. The discolored mica is generally used as insulation, and it may even be that the minerals causing the discoloration will render it unfit for that purpose, when it will be fit only for spangling paper, fabrics or the like.

By my process the cheap, discolored mica is split into lamellæ by any desired means. The sheets or scales, if two are to be used are then laid face to face but reversed one relatively to the other and secured together whereby the discolorations of one sheet will be visible through the other sheet and a more or less symmetrical design will appear on the laminated sheet.

If it be desired to make a more completely symmetrical design, four sheets reversed from side to side and from top to bottom may be employed whereby the discolorations will appear at four places.

In Fig. 1 of the drawings is shown a block 1 of mica having a discolored area 2 in one corner and a splotch 3 of color near the center thereof.

Figs. 2 and 3 show two sheets 4 and 5 split from the block, and Fig. 4 shows the said sheets in superposed relation but reversed as to the positions of discolored areas 2 and 3.

Fig. 5 shows four sheets 4, 5, 6 and 7 split from the block 1 and superposed one above the other and with the sheets reversed in both directions whereby the areas 2 will appear at the four corners of the laminated element, and the areas 3 will appear in four places.

When the sheets are separated from the block each sheet carries the same, or nearly the same, natural design. Should the sheets be superposed in the same position as they were split off the block, the design of the new, laminated structure would be exactly the same as that of the block.

When four sheets are arranged face-to-face as in Fig. 5, an entirely new design will appear for the reason that the designs of all of the sheets will appear each in a different position on the laminated structure and the new design will be composed of all of the original designs, each of the latter being viewed separately.

In Fig. 6 is shown a lamp shade composed of four panels 8 each consisting of a four ply laminated element cut to shape to form a panel 8, the lamellæ of each panel are secured together by means of a binding 9. One or both of the exposed surfaces of each panel is preferably rendered translucent, as to the naturally transparent portions of the same, by etching, sand blasting or the like.

Instead of mica any other naturally colored partly transparent or translucent material, such as an onyx, agate, cat's eye, serpentine, quartz, etc., may be employed, as shown in Fig. 7. It will be understood that with naturally translucent materials, such as most of those just above described, the step of sand blasting or etching may be omitted.

Instead of securing the sheets or lamellæ together by means of a binding strip, said sheets may be cemented or even fused together.

The invention while described as an article to be exhibited or displayed by transmitted light, is not limited to such use. In the case of semi-precious stones such as agate, cat's eye or the like, the article may be used as a doublet wherein the natural design of the stone will be improved or enhanced. In the case of a doublet the stone may be backed by a reflecting surface 10 as shown in Fig. 8.

The process and article of my invention are somewhat similar to wood veneering, with the important difference that in the present invention the lamellæ must have transparent or semi-transparent areas, and less transparent areas.

It will be understood that in the case of materials which are not capable of being split into lamellæ as is mica, the material will be sawed or otherwise cut into thin sheets or veneers.

It is to be further understood that the invention is not limited to bodies consisting of laminated sheets severed from the same parent block. The sheets may be severed from different blocks of the same material, or from different parts of the same block, or each lamellæ may be of a different material.

In the use of mica one or more of the lamellæ may be of a naturally tinted variety, such for example as lepidolite, or artificially colored sheets may be employed. When tinted sheets are used the sand blasting may be omitted.

In order to increase the diffusion of the light transmitted through a panel such as that shown in Figs. 5 and 6, one or both sides of any or all of the sheets may be etched or sand blasted. When the interior sheets are roughened the exposed surfaces of the panel may, if desired, remain untreated to prevent the accumulation of dust on said surface.

In accordance with the provisions of the patent statutes the principle of the invention has been described, together with the apparatus which is now considered to represent the best embodiment thereof, but it is desired to have it understood that the apparatus shown is merely illustrative, and that the invention may be carried out in other ways.

Having now described the invention, what is claimed as new and desired to be secured by Letters Patent, is as follows:—

1. The process of making a light transmitting body from a natural light transmitting product having unsymmetrical discolorations, which comprises separating the natural product into sheets, each of said sheets being approximately identical, reversing the sheets whereby the discoloration will appear in different portions of the sheets, and superposing one sheet over another to form a laminated structure showing the discolorations of all of the sheets in a more or less symmetrical design.

2. The process of making a light transmitting body from a natural light transmitting product having unsymmetrical discolorations, which comprises separating the natural product into sheets, each of said sheets being approximately identical, reversing the sheets whereby the discoloration will appear in different portions of the sheets, superposing one sheet over another to form a laminated structure showing the discolorations of all of the sheets in a more or less symmetrical design, and securing the sheets together.

3. The process of making a light transmitting body from a natural product having unsymmetrical discolorations, which comprises separating the natural product into sheets, such sheets having more or less transparent and more or less non-transparent portions, all of the sheets being approximately identical as to the locations of the transparent and non-transparent portions, reversing the sheets whereby the discolorations will appear in different portions of the sheets, superposing one sheet over another to form a laminated structure showing all of the discolorations, securing the sheets together, and rendering the transparent portions non-transparent.

4. The process of making a light transmitting body from a natural product having unsymmetrical discolorations, which com-

prises separating the natural product into sheets, such sheets having more or less transparent and more or less non-transparent portions, all of the sheets being approximately identical as to the locations of the transparent and non-transparent portions, reversing the sheets whereby the discolorations will appear in different portions of the sheets, superposing one sheet over another, 10 to form a laminated structure showing all of the discolorations, securing the sheets together, and roughening a sheet.

5. The process of making a light transmitting body from a natural product having 15 unsymmetrical discolorations, which comprises separating the natural product into sheets, such sheets having more or less transparent and more or less non-transparent portions, all of the sheets being approximately identical as to the locations of the transparent and non-transparent portions, reversing the sheets whereby the discoloration will appear in different portions of the sheets, superposing one sheet over another to 25 form a laminated structure showing all of the discolorations, securing the sheets together, and roughening a plurality of the sheets.

6. An article of the character described, 30 comprising a plurality of thin, more or less transparent sheets, each of the sheets having a zone of discoloration, said sheets being more or less similar as regards the size and location of the discolorations, said sheets being superposed one upon the other, but reversed relatively to each other whereby the 35 discolorations will not be in alinement, the

discoloration of one sheet showing through a transparent portion of another sheet.

7. An article of the character described, 40 comprising a plurality of thin, more or less transparent sheets, each of the sheets having a corresponding relatively non-transparent discoloration, said sheets being superposed one upon the other, whereby the discoloration of each sheet will show through a transparent portion of each other sheet, and means for securing the sheets together. 45

8. An article of the character described, 50 comprising a plurality of thin sheets of a natural product, said sheets being superposed one above the other, each sheet having an area less transparent than another area, said sheets being so arranged relatively to each other that like areas will not be alined. 55

9. An article of the character described, 60 comprising a plurality of thin sheets, said sheets being superposed one above the other to form a laminated structure, each sheet having an area less transparent than another area, all of the sheets being more or less identical as to said areas, there being a roughened surface on the structure, said sheets being so arranged relatively to each other that like areas will not be alined, and 65 means for securing the sheets together at the edges.

This specification signed and witnessed this 28th day of June, 1922.

AARON P. STORRS.
